UNITED STATES PATENT OFFICE.

LOUIS MARKS, OF SAN FRANCISCO, CALIFORNIA, ASSIGNOR OF ONE-HALF
HIS RIGHT TO R. R. STRAIN.

IMPROVEMENT IN CARBURETERS.

Specification forming part of Letters Patent No. 156,463, dated November 3, 1874; application filed
July 28, 1874.

To all whom it may concern:

Be it known that I, LOUIS MARKS, of San Francisco city and county, State of California, have invented a Carbureter; and I do hereby declare the following description and accompanying drawings are sufficient to enable any person skilled in the art or science to which it most nearly appertains to make and use my said invention without further invention or experiment.

My invention relates to certain improvements in that class of machines which are employed to saturate air with the vapor of the light hydrocarbon oils for the purpose of producing an illuminating gas, these machines being known as carbureters; and my invention consists in the particular combination and arrangement of parts hereinafter described.

Referring to the accompanying drawing for a more complete explanation of my invention—

Figure 1 is a perspective view, with a portion broken away. Fig. 2 is a section of the valve-chamber, showing the valve. Fig. 3 is a bottom view, showing the pipes P.

A is the outer or containing vessel, for holding the liquid; and B is an interior air-chamber. The outer vessel is kept filled with liquid from a reservoir by means of a pipe, C, through which it is conducted. This pipe has two branches, one, F, extending down by the side of the vessel A, for a purpose hereafter described, while the other opens into a valve-box, D, at the top of the chamber A. A stop-cock, E, prevents the flow of the liquid into the pipe F until it is desired. The box D is provided with a valve, i, which closes upward. A long stem, G, extends downward from this valve, and is provided with a float, H, within the containing-chamber A.

By the operation of this float the valve i is closed, and the flow of liquid stopped whenever the chamber is filled to the desired height.

Air is furnished to the machine by a suitable apparatus; and is conveyed from the receiver (not shown) to the air-chamber B by a pipe, K. From the top of the air-chamber pipes L lead to the bottom of the chamber A, where they enter the conical perforated or wire screens R, which serve to distribute the air throughout the liquid, so that it becomes thoroughly saturated with vapor from every

part as it rises to the surface. As the air or gas rises to the top of the vessel A, it is allowed to pass up, through the pipe M, into the gasometer N. From this gasometer the gas is passed out, through the pipe O, to the distributing-main.

As the liquid becomes relieved of its more volatile portions it acquires a greater specific gravity, settles to the bottom, and ceases to be valuable for producing purposes, but can still be utilized for mixing with the more volatile portions, and occupying a portion of the space, so that it will not be necessary to introduce so much fresh liquid as would be the case if all of this heavy portion were withdrawn.

For the purpose of concentrating the heavy liquid at the bottom, I employ pipes P beneath the bottom of the chamber A, which receives a part of this liquid as it settles.

In order to stir it up, and mix it thoroughly with the lighter liquid in the vessel A, I open the stop-cock E at certain periods, and allow the fresh liquid to enter the pipe F. This pipe connects with the pipes P, and the current of new liquid being admitted under the heavy residue, has the effect to force upward all the heavy residue, and mix it with that contained in the reservoir A above. This can be done at any time desired or needed.

Having thus described my invention, what I claim, and desire to secure by Letters Patent, is—

1. The carbureter as above described, and consisting of the pipe C, receiver D, with its upwardly-closing valve i, rod G, and float H, within the chamber A, in combination with reservoir B, with the pipes L L, having the perforated screens R, the conducting-pipe F, and the pipes P, all constructed and arranged substantially as and for the purpose set forth.

2. The side conducting-pipe F, in combination with the system of half-pipes P below the bottom of the vessel, substantially as and for the purpose set forth.

In witness whereof I hereunto set my hand and seal.

LOUIS MARKS. [L. S.]
